UNITED STATES PATENT OFFICE.

KENNIE H. DELOATCH, OF WASHINGTON, DISTRICT OF COLUMBIA.

GATE-LATCH.

1,235,560.

Specification of Letters Patent.

Patented Aug. 7, 1917.

Application filed July 24, 1916. Serial No. 111,078.

To all whom it may concern:

Be it known that I, KENNIE H. DELOATCH, a citizen of the United States, residing at Washington, in the District of Columbia, 5 have invented certain new and useful Improvements in Gate-Latches, of which the following is a specification.

This invention contemplates an improved gate latch and has as its primary object to 10 provide a device of this character adapted for use in connection with any conventional type of gate as now employed and wherein the latch will efficiently act to lock the gate shut upon the closing thereof.

15 The invention has as a further object to provide a device of this character which may be readily operated from either the inside or the outside of the gate and wherein the latch may be easily applied without the necessity for any structural change in the gate.

20 Other and incidental objects will appear as the description proceeds and in the drawings wherein I have illustrated the preferred embodiment of the invention and wherein similar reference characters designate corresponding parts throughout the several views,

25 Figure 1 is a perspective view on a slightly enlarged scale and more particularly showing the mounting of the operating lever for actuating the latch,

30 Fig. 2 is a side elevation more particularly showing the arrangement and mounting of the latch,

35 Fig. 3 is a sectional view showing the manner in which the link for connecting the operating lever of the latch with the catch member is adapted to provide a stop for the 40 said catch member limiting the catch member in its movement to active position, and

45 Fig. 4 is a fragmentary detail perspective view of the said link.

In carrying out the invention, I employ a 50 bracket 10 preferably formed from a strip of suitable sheet metal bent intermediate its ends to provide parallel arms. The free extremities of these arms may be connected to a gate post in any suitable manner as 55 illustrated in the drawings, and in order that the construction, mounting, and operation of my improved latch may be more clear, I have conventionally illustrated a gate 11 which is provided with a striking bar 12 fixed to 60 the gate adjacent the free side thereof and forming a movable element swinging with 65 the gate. This bar 12 is, at its free end, arranged to coöperate with the gate post 13, for limiting the gate in its swinging movement to closed position. It will now be observed that the arms of the brackets 10 are offset adjacent their inner extremities to provide shoulders 14 seating against the front face of the gate post 13 with the adjacent ends of the arms connected to opposite sides of the said posts to support the bracket projecting laterally in front of the post.

70 Freely mounted between the arms of the bracket 10 is a catch 15, pivotally connected adjacent its outer extremity to the outer end of the bracket by a rivet or other suitable fastening device 16 which extends through the bracket arms. The inner end of the catch terminates short of the shoulders 14 of the 75 bracket to receive the bar 12 of the gate, as particularly shown in Fig. 1 of the drawings, and is formed with a straight edge to engage with the said bar. The lower edge 17 of the catch member is longitudinally inclined in a downward direction from the outer end of the said catch member toward its inner end. The purpose of this construction will presently appear.

75 Mounted upon the bracket 10 adjacent the outer extremity thereof, is an upwardly projecting and rearwardly inclined post 18. This post is preferably formed from a strip of metal similar to that employed in constructing the bracket 10 and may be riveted 80 or otherwise suitably secured to the adjacent arm of the bracket upon the outer side thereof. Arranged upon the post 18 is an operating lever 19 for the catch. This lever is somewhat U-shaped in general contour, 85 being formed with downwardly directed arms 20 and 21 respectively with the bight portion of the said lever pivotally connected by a rivet or other suitable fastening device to the upper extremity of the said post. 90 The arm 20 is slightly shorter than the arm 21 and, at its free extremity, is formed with a laterally and forwardly directed extension 22. Extending laterally from the body of the latch in a direction opposite the arm 22 95 is a rearwardly directed finger receiving lug or handle 23. Connecting the extension 22 of the lever 19 with the catch 15, is a link 24. This link, as shown in detail in Fig. 3 of the drawings, is, at its lower extremity, 100 pivotally connected to the upper edge of the catch 15 adjacent the forward end of

the said catch while the upper extremity of the said link is formed with an eye or loop 25 which freely receives the extension 22. The eye is, as particularly shown in Fig. 2 5 of the drawings, offset to form a shoulder 26 engageable with the upper edge of the outermost arm of the bracket 10 for limiting the catch 15 in its downward pivotal movement to active position.

10 As will now be seen, the catch member 15 may be easily lifted by pressing downwardly upon the lug 23 of the lever 19. Such pressure upon the lug will swing the said lever upon its pivot to raise the extension 22 of the arm 20. This extension will then slide through the eye 25 of the link 24 to lift the catch member and free the striking bar 12 of the gate. Upon the release of the lug 23, the catch will then 15 gravitate to active position to be limited in its movement by the shoulder 26 of the link 24. In this connection, it will be observed that the link 24, therefore, performs a dual function since it not only provides a connection between the operating lever and the catch, but also provides a stop member for 20 limiting the catch in its movement to active position.

15 The purpose in forming the catch member with the longitudinally inclined edge 17 will now become apparent. Since the said catch will, under normal conditions, automatically move to active position, it will very often occur that the gate will be 20 open with the said catch disposed in the path of movement of the striking bar 12 when the gate is closed. However, when so moved, the bar 12 will engage the edge 17 of the catch to automatically lift the catch 25 upwardly and permit the inward shifting of the said bar to abut the post 13 when the catch will immediately drop in front of the bar to hold the gate shut.

20 Connected to the free end of the arm 21 of the operating lever 19, is a latch string 27 which may, if desired, be loosely attached to the post 13 and terminates at the inner side of the gate. While I have defined the element 27 as a latch string, still, it will be 25 understood that any suitable flexible element may be employed or if desired, a short length of rod may be substituted for the said string. By pulling upon the string 27, the lever 19 will, as will be understood in 30 view of the previous description be shifted to raise the catch 15 and release the gate.

35 It will therefore be seen that I provide a very simple and efficient construction for the purpose set forth and a device which 40 may be readily attached to and employed in connection with conventional types of gates as now in common use, without the necessity of structural change therein. Fur-

thermore, it will be seen that the latch may be operated from either the inside or the 65 outside of the gate, and that normally, the said latch will automatically act to lock the gate shut upon the closing thereof.

Having thus described my invention, what I claim and desire to secure by Letters Pat- 70 ent is:

1. A device of the character described including a supporting bracket, a catch pivotally connected to the bracket and normally gravitating to active position thereon, a 75 pivoted operating lever for the catch, and means slidably connecting the lever with the catch and offset in the direction of the mounting of said lever to provide a stop adapted to coöperate with the bracket for 80 limiting the catch in its movement to active position.

2. A device of the character described including a supporting bracket, a pivoted catch member gravitating to active position 85 thereon, a pivoted operating lever having downwardly directed arms formed thereon with the said arms extending below the pivotal center of the catch member, means slidably connecting one of said arms with the 90 said catch member, and means connected to the free extremity of the other of said arms for actuating the said lever to lift the said catch member.

3. A device of the character described including a supporting bracket having spaced arms, a catch member pivoted between the said arms and normally gravitating to active position thereon, an upstanding post carried by the said bracket, a pivoted operating lever mounted upon the said post with a fixed center and having downwardly directed arms formed thereon, a link carried by the catch member and slidably engaging one of said arms with the said link providing a stop adapted to coöperate with the said bracket for limiting the catch member in its movement to active position, and means connected to the other of said arms for shifting the said lever to lift the catch mem- 105 ber.

4. A device of the character described including a supporting bracket, a pivoted catch member mounted thereon and normally gravitating to active position upon 115 the bracket, an upstanding post carried by the bracket, a substantially U-shaped operating lever pivoted at its bight to the said post with the arms of the said lever extending downwardly, an extension carried by 120 one of said arms and slidably connected with the said catch member, and means connected to the other of said arms for rocking the said lever to actuate the catch member.

In testimony whereof I affix my signature. 125
KENNIE H. DELOATCH. [L. S.]
